UNITED STATES PATENT OFFICE.

OTTO G. VOSS, OF CLEVELAND, OHIO.

PRESS.

Application filed December 26, 1916. Serial No. 138,714.

To all whom it may concern:

Be it known that I, Otto G. Voss, a citizen of the United States, residing at Cleveland, in the county of Cuyahoga and State 5 of Ohio, have invented a certain new and useful Improvement in Presses, of which the following is a full, clear, and exact description.

This invention relates to presses such as 10 are used by clothing manufacturers for pressing outer garments, or by laundries for the purpose of pressing laundry work.

The principal object of the invention is to provide certain improvements which facilitate 15 the operation of the press and increase its efficiency and output. Another object is to render the press easier to operate, that is to say, to relieve the operator of much of the manual labor heretofore required and to 20 minimize the movements or the manipulation of controlling devices in pressing a garment or a series of garments. A still further object is to provide a control for the power operated portion of the press, which 25 automatically times the pressing operation and prevents a garment being pressed between the buck and the co-operating pressing member, whether it be in the form of an iron or ironing head, for a period of time 30 which is either less or greater than that desired.

The invention, briefly stated, comprises certain novel details of construction and combinations and arrangements of parts 35 which will be described in the specification and set forth in the appended claims.

In the accompanying sheets of drawings wherein I have shown several embodiments of my invention, Fig. 1 is a side 40 view of a press embodying my invention, and adapted particularly for pressing outer garments; Fig. 2 is a perspective view of the upper portion of the machine illustrated in Fig. 1; Fig. 3 is a side view with parts broken away showing a 45 press embodying my invention and adapted particularly for laundries; Fig. 4 is a top plan view of the same; Fig. 5 is a diagrammatic view showing the electric circuits, 50 switches and other elements used in the control of the press, this view illustrating the system of control which automatically times the pressing operation; Fig. 6 is a similar diagrammatic view showing the system of 55 control wherein the time of the pressing operation is controlled by the operator through

a manually operated switch in the handle of the movable pressing member; Fig. 7 is an enlarged view of the handle of the press with parts broken away, illustrating a manually operated switch which may be utilized to advantage in the system having the automatic time control; Fig. 8 is a similar view showing the switch which may be used to advantage in the system of control wherein the operator times the length of the pressing operation; and Fig. 9 is a cross-sectional view through the handle of Fig. 8, showing the manner in which the switch is opened and closed manually. 70

In Figs. 1 and 2 I have shown my invention embodied in a press adapted especially for use by clothing manufacturers, tailors and the like, for pressing outer garments. This press includes a bed or frame 10 on 75 which is suitably supported a buck 11, to which, if desired, a heating medium may be supplied, as for example, live steam or gas through a pipe 12 shown in Fig. 2. The heating of the buck may be dispensed with, 80 or if desired, it may be heated by some other medium than the ones referred to.

In the different forms of my invention the pressing member which co-operates with the buck is power operated, and although it is 85 immaterial to my invention in its broadest aspect what type of power or source of power is used to create the pressure between the pressing member and the buck, I prefer that this be accomplished electrically through 90 a large pressing magnet 13 which is supported in the lower part of the frame 10.

In Figs. 1 and 2 the pressing member is in the form of an iron 14 which may be heated in any suitable manner, such as electrically 95 or by steam or gas. In Fig. 2 the iron has connected to it a conduit 15 which may convey the heating medium or carry the conductors for heating the iron electrically. The iron is carried on the lower end of a vertical threaded shaft 16, provided at its upper end with an adjusting hand wheel 17 and mounted for adjustment vertically in the outer end of an arm 18 designed to be moved inwardly and outwardly with respect to, and having 100 a sliding engagement with an arm or bracket 19 which is pivoted to swing about a vertical axis. The arm 19 is pivotally supported by vertically aligned trunnions 20 on the upper part of a rather heavy yoke 21 which is pivotally supported to move about a horizontal axis on brackets or standards 22 mounted on 105 110

and projecting upwardly from the rear part of the bed 10, the yoke having trunnions 23 mounted in bearings at the upper ends of the standards or brackets 22. The lower part of the yoke extends downwardly and forwardly through the bed or frame 10, and at its lower forward end is provided with an enlargement 24, which is directly above the pressing magnet 13 and constitutes an armature co-operating therewith. It may be here stated that when the magnet 13 is energized, the armature end of the yoke is drawn down toward the magnet pulling the pressing member 14 firmly down onto the buck. 10 The pressing member and the yoke supporting it are preferably so counterbalanced that they can be easily shifted about the axis of the trunnions 23. Likewise, the pressing member can be readily moved about 15 the vertical axis of the trunnions 20 to move the pressing member lengthwise of the buck, and the arm 18 is mounted to slide easily in the arm or bracket 19 to permit the pressing member to be moved to any point on 20 the buck. 25

The pressing member 14 is provided with a handle 25 which is grasped by the operator to move the iron with respect to the buck, and which preferably has incorporated in it a controlling switch so that it can be manipulated, that is, either opened or closed by the operator with the hand placed on the handle to move the iron about, and without requiring the removal of his 30 hand from the handle. 35

Before describing the control of the pressing member and the type and number of switches which are utilized therein, reference is had to Figs. 3 and 4, showing the press adapted for pressing various kinds of garments and cloth including laundry work. This press as here shown is provided with a base 30 on the upper part of which is supported by means of a suitable bracket 31, the lower buck 32. Co-operating with the buck 32 is an upper buck or pressing head 33 secured to an arm or lever 34, pivoted at 35 on brackets 36 on the upper part of the base 30 so as to swing about a horizontal axis, and provided with a movable counterweight 37. 40

By means of the counterweight 37 the upper buck is counterbalanced so that it can be easily moved up or down by the operator grasping a handle 38 in which is preferably incorporated the controlling switch, to be referred to presently, so that by the same movement and by the hand which lowers the buck, the switch can be manipulated to 45 control the source of power which pulls the buck down with the requisite pressure onto the lower buck to perform the pressing operation. In this instance as in the prior construction, the movable pressing member, that is to say the upper buck 33 is pulled down 50

onto the lower buck by a magnet 13, which as here shown, is mounted in the lower part of the base 30, said magnet having a co-operating movable armature 39 which in this case is connected by a rod 39^a to the lever 34 which carries the movable buck. The pressure of the upper buck on the lower buck can be adjusted when desired, by turning a turn-buckle 39^b in the rod 39^a. This adjustment is an important feature especially as an adjustment of the armature which varies very slightly the air gap between the magnet and armature when the magnet is energized and the pressing members are in engagement producing a very wide variation of magnetic pull on the armature and hence on the buck. 70 75 80

Steam or other heating medium will be supplied to both bucks in the customary manner in machines of this type, but as the supplying of the heating medium to the bucks does not constitute any part of the present invention, it will not be described in detail, the pipes for supplying the heating medium being designated as a whole 85 by the reference character 40. 90

In the control of the movable pressing member of the press either in the form illustrated in Figs. 1 and 2, or in the form illustrated in Figs. 3 and 4, I use an electrically controlled or an electro-magnetic switch 41 which is designed to open and close the circuit between the pressing magnet 13 and the main current supplying conductors 42 and 43 which may be conductors of an ordinary direct current lighting system. The switch 41 is opened either by gravity or by gravity assisted by a spring 41^a and is closed by an electro-magnet 41^b, the switch having a movable switch member 41^c which is connected to a conductor 44 leading to the pressing magnet 13 and a contact 41^d, which is connected to one of the main current supplying conductors 43. 95 100 105

In addition to the switch 41 I employ a manually operated switch 45 and preferably also an automatic time limit switch 46 which is normally closed, being closed by gravity, or by gravity assisted by a spring 46^a (see Fig. 5) and is opened by the plunger of a solenoid 46^b. The solenoid 46^b has associated with it a dash pot or equivalent time limit device, and in this case the plunger 46^c of the solenoid has connected to its lower end a dash pot piston 46^d which moves in a cylinder or casing 46^e adapted to contain oil or other fluid which will cause the piston to move slowly for a given interval of time when the piston is moving in one direction, and then allow the piston to complete its movement in the same direction quickly. In the embodiment of the invention shown in Fig. 5, the plunger will move upward slowly for a period, and then will complete its forward stroke with a quick 110 115 120 125 130

movement, and in so doing, it strikes the movable contact member 46^a of the time limit switch 46 so as to move it away from the stationary contact 46^b. As here shown, 5 the movable member of switch 46 is connected by a conductor 47 to one of the main current supplying conductors 42, and the stationary contact 46^b of this switch is connected by a conductor 48 to one terminal 10 of the coil of the electro-magnet 41^b of switch 41, the other terminal of the coil being connected to conductor 44. One terminal of the coil of the solenoid 46^b associated with switch 46 is connected to the conductor 47 leading to the main conductor 42, and the other terminal of the solenoid coil is connected to the conductor 44. The switch 45 is connected in shunt around the switch 41, the movable contact member 45^a of the 15 switch being connected to conductor 43 and the stationary contact 45^b being connected to conductor 44. The switch 45, as shown in Fig. 7 and also diagrammatically in Fig. 5, is closed manually and opened by a spring 20 45^c as soon as the push button 45^d is released by the operator.

It will be seen therefore, that with this arrangement normally the circuit of the pressing magnet 13 is open, the switches 41 and 45 then being open and the switch 46 closed. When the operator desires to have the movable pressing member pulled downward onto the buck, he closes the manually operated switch 45. This completes the circuit around the switch 41, causing a shunt or comparatively high resistance circuit to be completed through the coil of the actuating magnet 41^b of switch 41. This causes the instant closure of the switch 41 and the 25 completion of the main circuit through the pressing magnet 13. Upon the closure of the switches 45 and 41, another comparatively high resistance circuit is completed through the coil 46^b of the solenoid associated with the switch 46. The solenoid thus 30 being energized, the plunger thereof begins to travel upwardly, and after a predetermined interval of time it strikes with a blow the movable switch member 46^a of switch 46, causing said switch to be opened and breaking the circuit through the coil of magnet 41^b of switch 41, causing said switch to be opened and also causing the de-energization of the magnet 13. It may be stated 35 at this point, that previous to the opening of the switch 41 in the manner just described, the hand operated switch 45 will be opened, because it is only necessary for the operator to close the switch 45 with his 40 thumb or finger, and then immediately thereafter release the button 45^d and permit the switch 45 to be opened. The main switch 41, however, remains closed for a predetermined interval of time, after which the switch 46 opens the shunt circuit

through the coil of the magnet controlling the switch 41, causing the opening of the latter and the cessation of the pressing operation. This also de-energizes the solenoid of switch 46 and the plunger then drops 70 back to normal position. The operator can then repeat the pressing operation which continues for a given interval of time as above explained, by again closing the switch 45. 75

A valve is preferably associated with the piston 46^a so that the piston while moving slowly upward with the plunger, will drop back or move downward to normal position relatively quickly. 80

The interval of time that the switch 41 remains closed after the energization of the solenoid of switch 46 can be varied in numerous ways, such for example, as by a rheostat or adjustable resistance R, Fig. 5, 85 in the shunt circuit of the solenoid coil.

The manually operated switch 45 is preferably embodied in the handle 25 of Figs 1 and 2, or 38 of Figs. 3 and 4. By reference to the detail view of Fig. 7 it will be seen that the contacts of switch 45 are arranged in a casing 45^e at one end of the handle, and that the operating stem for the switch extends through the handle and is provided at the opposite end of the handle with the push 90 button 45^d. While I do not wish to be confined to this construction of switch the arrangement here illustrated has proven to be very effective. In operating the press of Figs. 1 and 2 the operator will generally 95 keep his hand on the handle, and with his thumb will press the push button inward to close the switch 45, and then release the push button whereupon the pressing member is pulled down onto the buck and when the 100 pressing member is released after a predetermined interval of time, the operator will move the iron to another point on the buck, and again press the button and then release it. In this manner the pressing of a large 105 garment or a series of garments can be done rapidly, although each time the desired pressing period elapses before the pressing member is released. In operating the press of Figs. 3 and 4, the operator will, by grasping the handle, pull the buck downward and at the same time close the switch, whereupon the upper buck or pressing head is held or pulled down on the lower buck, and after a 110 predetermined interval of pressing has elapses, the pressing member will automatically swing upward away from the lower buck by the action of the counterweight.

The system of control wherein the pressing member is held down onto the buck for 125 a predetermined interval of time is very useful in doing certain kinds of pressing work, particularly when the operator is doing piece work, that is, is paid by the number of garments which are pressed. With the prior 130

1
0
presses wherein the length of pressing operation is controlled by the operator there is often a tendency for the operator to press a garment or part of a garment an insufficient length of time in order that a large number of garments may be pressed, but with the automatic time limit or press timing arrangement herein provided this difficulty is very effectively overcome.

10 Under certain circumstances it is desirable that the operator control the time of the pressing operation, particularly in doing certain kinds of pressing, such as the so-called seam pressing, wherein the operator 15 moves the pressing member rapidly along the seam, it being necessary that the pressing member be held down only for an instant, or a very short interval of time. For this kind of work I arrange the controlling switch in 20 the handle as in the time limit arrangement first described, but employ a switch which the operator closes and opens while maintaining his hand on the handle. This arrangement last referred to is illustrated in 25 Figs. 6, 8 and 9. By referring to Fig. 6 particularly, it will be seen that the time limit switch is eliminated, and that the system of control for the pressing magnet 13 includes only the electro-magnetic switch 41, 30 which as in the first arrangement opens and closes the circuit for the pressing magnet, and the manually controlled switch here designated 50. This switch as here shown includes two stationary contacts 50^a and 50^b, 35 and a movable switch member 50^c, which is opened and closed by a pair of push buttons 50^d and 50^e. This switch 50 is connected in series with the coil of the electro-magnet 41^b, in a high resistance shunt circuit connected 40 across the conductors 42 and 43. This switch is preferably incorporated in the handle of the press in the manner illustrated in Figs. 8 and 9 with the two push buttons extending through the handle at 45 diametrically opposite points.

It will be obvious that the operator can open and close the switch and thus cause the pressing member to be pulled downward onto the buck, and then released as rapidly 50 as the character of the work will permit.

I do not desire to be confined to the exact details shown, as variations in the construction and arrangement will suggest themselves to one skilled in the art, and I aim 55 therefore in my claims to cover all modifications which do not involve a departure from the spirit and scope of my invention.

Having thus described my invention, what I claim is:

60 1. In a press, a pair of pressing members, one of which is movable with respect to the other, means for causing a pressing action between the same for a predetermined interval of time, said means comprising a motive device which is operatively connected

to the movable pressing member, means by which energy may be supplied to said motive device, and means for automatically causing the de-energization of the motive device at the end of said predetermined interval of time so as to terminate the pressing action. 70

2. In a press, a pair of co-operating pressing members one of which is movable with respect to the other, a motive device connected to the movable pressing member for causing a pressing action between the two pressing members, means under the control of the operator for causing the motive device to be connected to a source of power 75 so as to receive energy from the latter, and means for automatically disconnecting the motive device and source of power after a predetermined pressing action has occurred so as to deenergize the motive device and 80 terminate the pressing action.

3. In a garment press, a pair of co-operating pressing members one of which is movable with respect to the other; electro-magnetic motive means acting upon the 85 movable pressing member for causing a pressing action between the two pressing members, conductors for connecting the motive means to a source of current supply, and means for controlling said motive means including a switch for automatically disconnecting the motive means from the source of current supply after a predetermined interval of time from the beginning 90 of the pressing action so as to deenergize the motive means and terminate the pressing action. 100

4. In a garment press, a pair of co-operating pressing members one of which is movable with respect to the other, electro-magnetic motive means acting upon the 105 movable pressing member for causing a pressing action between the two pressing members, and means for controlling said motive means including a manually controlled switch for starting the pressing action, and an automatic switch for stopping the pressing action after a predetermined length of pressing action between 110 said pressing members. 115

5. In a garment press, a pair of co-operating pressing members one of which is movable with respect to the other, electro-magnetic motive means associated with the movable pressing member for causing pressing action between said pressing members, an electrically operated switch for connecting said motive means to a source of current, a manually operated switch for controlling the closure of said electrically operated switch, and an automatic switch for causing the opening of said electrically operated switch a predetermined time after the closure thereof. 120

6. In a press, a pair of co-operating press-

- ing members one of which is stationary and the other movable with respect thereto, a magnet having a member connected to the movable pressing member, and switching means for controlling the energization of said magnet and comprising a switch for automatically causing the de-energization of said magnet a predetermined time after the magnet is energized.
- 10 7. In a press, a stationary pressing member, a movable pressing member, a magnet having an armature connected to said movable pressing member and adapted to cause the same to be held against the stationary
- 15 pressing member for garment pressing purposes, an electrically operated switch for closing the circuit between said magnet and a source of current supply, a manually operated switch for causing the closure of said electrically operated switch, and an electrically operated switch for automatically causing the opening of said first-named electrically operated switch.
8. In a press, a frame, a buck supported on said frame, a movable pressing member,
- 5 a power device operatively connected thereto and adapted to hold the same against the buck with predetermined pressure, a main controlling device for the power device, said movable pressing member having a handle 30 by which it may be moved relative to the buck, and a controlling element carried by said handle for controlling the main controlling device.
9. In a press, a buck, a pressing member 35 movable with respect to the buck and provided with a handle for shifting the same, electro-magnetic means operatively connected to said movable pressing member for pressing the latter against the buck, an 40 electrically operated switch for controlling the electro-magnetic means and an electric switch for controlling the first mentioned switch, said second mentioned switch being carried by the handle and having a movable 45 operating member adapted to be shifted by the hand of the operator when grasping said handle.

OTTO G. VOSS.
